UNITED STATES PATENT OFFICE.

GUNNAR MADVIG, OF OAKLAND, CALIFORNIA.

DESIGN FOR A CURTAIN-POLE END.

Application filed February 23, 1928. Serial No. 25,535. Term of patent 3½ years.

To all whom it may concern:

Be it known that I, GUNNAR MADVIG, a subject of the King of Denmark, and a resident of the city of Oakland, county of Alameda, State of California, have invented a new, original, and ornamental Design for a Curtain-Pole End, of which the following is a specification, reference being had to the accompanying drawings, forming part thereof.

Figure 1 is a side view of the curtain pole end illustrating my new design.

Figure 2 is a plan view of the curtain pole end.

I claim:

The ornamental design for a curtain pole end substantially as shown.

GUNNAR MADVIG.
